CLAIM

We claim the ornamental design for a display and key array cover for a wireless handset, as shown.

DESCRIPTION

FIG. 1 is a right front perspective view of the cover included within a phantom view of an exemplary wireless handset;

FIG. 2 is a front view of the cover;

FIG. 3 is a right side view of the cover;

FIG. 4 is a left side view of the cover;

FIG. 5 is a top view of the cover; and,

FIG. 6 is a bottom view of the cover.

The broken line showing of a phantom, exemplary wireless handset in FIG. 1 is for illustrative purposes only and forms no part of the claimed design.
